UNITED STATES PATENT OFFICE.

JOHN SHERRY, OF ROCHESTER, NEW YORK.

TORCH.

SPECIFICATION forming part of Letters Patent No. 529,631, dated November 20, 1894.

Application filed June 16, 1894. Serial No. 514,822. (No model.)

To all whom it may concern:

Be it known that I, JOHN SHERRY, of Rochester, in the county of Monroe and State of New York, have invented a certain new and useful Improvement in Torches; and I do hereby declare that the following is a full, clear, and exact description of the same, reference being had to the drawings accompanying this application.

10 My improvement relates to that class of lighting and heating devices in which the liquid is forced by atmospheric pressure upward to a burner where it is vaporized and the gas discharged in a jet which serves to produce the vaporizing action.

The invention consists in the special construction of the burner as hereinafter described and embodied in the claim.

In the drawings—Figure 1 is a side elevation, partially in section, of the apparatus. Fig. 2 is an enlarged longitudinal section of the burner. Fig. 3 is a cross section of Fig. 2 in line *x x*.

15 *A* indicates the tank, which may be of any suitable form and provided with a handle *a* by which it is carried.

20 *B* is a pipe extending down nearly to the bottom of the tank, as in others of this class of apparatus, being also provided with a cut-off *b* by which the passage of the fluid is regulated.

25 *C* is a pipe through which air is forced by a pump or otherwise to the interior of the tank over the oil to produce the necessary pressure to raise the latter to the burner. The tube is provided with a cut-off *c* by which a charge of air can be retained.

30 The burner is attached to the top of the pipe *B* and stands horizontally as shown. It consists of two cylindrical tubes *D* and *E*, fitted one within the other, leaving a thin annular jacket space *d* between them. This jacket space is closed at both ends, which is effected by fitting a shoulder *f* on the exterior 35 of the inner tube closely within the outer tube at one end, bringing a second and larger shoulder *f'* of the inner tube against said end of the outer tube, and uniting the ends of the two tubes at the opposite end by a screw 40 thread *g*. By this construction the two tubes

can be separated by making two or three turns of the outer one to disconnect the screw threads.

The oil is forced up through the pipe *B* into the annular space *d* between the tubes, where it is separated and spread. At the top the gas which is produced by the vaporization of the oil is carried off through a conduit *h* on top of and integral with the outer tube, thence outward through a pipe *G*, which is screwed 55 into the conduit *h* and is recurved at the outer end, and thence is discharged through a nipple *K*, which is so directed, centrally, as to blow the gas through the interior passage of the inner tube, which is open at both ends. 60 The flame is ejected at the outer end of the tubes as shown in Fig. 1.

65 *H* is a shield, such as is ordinarily employed in this class of apparatus.

70 *I* is a hood, closed on the sides and outer end, the inner end being open and of proper shape to slide forward and back on the ends of the larger shoulder *f'*, outer tube *D*, and conduit *h*. It incloses the gas pipe and nipple and forms, in fact, an extension of the 75 outer tube. In its sides are made longitudinal slots *m m*, which form the vent openings to admit the outside air. By adjusting the hood endwise on the tubes more or less of the length of the slots is cut off, thereby grading the admission of air and consequently regulating 80 the flame. The gas being blown through the tubes *D E* from end to end creates great heat inside the tubes, in addition to the blaze outside, and this intense heat vaporizes the oil, 85 which is carried up and spread through the thin annular space *d* between the tubes. A very great radiating surface is obtained by the simplest construction. Therefore all the oil which enters the space is at once converted 90 into gas, which, in turn, serves as the combustible agent to produce the heat. This construction is such that the parts are readily cleaned of the soot and sediment produced by the burning of oil between the tubes. The 95 hood *I* is first removed, the pipe *G* turned to one side, and then the tubes are separated by unscrewing them and removing the inner one endwise, and the whole surface of both tubes can then be brushed or wiped free of dirt 100.

without trouble. Much difficulty has been experienced in cleaning burners of the ordinary kind, owing to their intricate passages.

Having described my invention, what I claim as new, and desire to secure by Letters Patent, is—

In a vapor burner, the combination with a horizontal outer tube having one end reduced and interiorly screw-threaded, an oil supply pipe opening through the bottom of said tube near its center, and a conduit formed upon the top of said tube and extending from one end thereof to the center where it opens into said tube; of a second tube removably inserted within said outer tube and engaging the threads at one end, the exterior diameter of said inner tube being smaller than the interior diameter of the outer tube so as to form an annular space between the tubes, a shoul-

der on the inner tube closing the end of the annular space opposite from the threads, a second shoulder on the inner tube abutting against the end of the outer tube, a pipe screwed into the end of said conduit with its body recurved and carrying a nozzle directed through the inner tube, and a hood inclosing the pipe and nozzle and shaped so as to fit close around and slide longitudinally over the inlet end of the outer tube and conduit, said hood having air inlets at its inner end, as and for the purpose set forth.

In witness whereof I have hereunto signed my name in the presence of two subscribing witnesses.

JOHN SHERRY.

Witnesses:

JOHN F. DAKE,
R. F. OSGOOD.
